CLAIM

The ornamental design for a vehicle control arm bushing, as shown and described.

DESCRIPTION

FIG. 1 is a front perspective view of a vehicle control arm bushing showing our new design;

FIG. 2 is a front elevational view thereof, the rear elevational view being identical;

FIG. 3 is a top plan view thereof, the bottom plan view being identical;

FIG. 4 is a left side elevational view thereof the right side being identical;

FIG. 5 is a front perspective view of another embodiment of the vehicle control arm bushing;

FIG. 6 is a front elevational view thereof, the rear elevational view being identical;

FIG. 7 is a top plan view thereof, the bottom plan view being identical; and,

FIG. 8 is a left side elevational view thereof the right side being identical.
